SUPPORT AND CONTROL FOR ELECTRICAL APPLIANCES

Edwin H. Dreyer, Chicago, Ill., assignor of thirty percent to Edward F. Hendee, Chicago, Ill.

Application December 31, 1937, Serial No. 182,846

11 Claims. (Cl. 200—33)

The present invention relates to a support and control for an electrical appliance, and more particularly to a device for controlling the supply of electric current to the appliance.

In the average home, one of the most common, dangerous and costly oversights exists in connection with the use of certain types of electrical appliances. Frequently, the user, due to various distractions about the house, or due entirely to inadvertence, leaves an appliance, such as a sadiron, connected to the electric current supply for relatively long periods of time without using it, and, in many instances, leaves the home for substantial periods, with the appliance connected to the energy source. It is a well recognized, unfortunate but common occurrence to leave a sadiron in operation unintentionally, resulting in burning of fabric, padding, ironing boards, and, in some instances, after prolonged periods, burning through the floor of the home. In addition to attendant fire hazards and damage, there is also present the element of waste of electric current.

One of the objects of this invention is to provide a novel structure of the character indicated, which obviates the foregoing difficulties.

Another object resides in the provision of a novel device of the character described, having means for interrupting the current supply to the appliance after said appliance remains on the support for a predetermined period of time.

A further object is to provide a novel support and control for an electrical appliance, having means for varying the period of time before causing interruption of the current supply, in connection with an appliance of given weight.

Other objects and advantages of the present invention will appear from the following description, taken in connection with the accompanying drawings, in which:

Fig. 1 is a perspective view of a portion of an ironing board with which is associated a sadiron carried on the support and control device, embodying the present invention.

Fig. 2 is a top plan view of my novel support and control device.

Fig. 3 is an enlarged vertical section through the device, taken as indicated at line 3—3 on Fig. 2.

Fig. 4 is a horizontal section through the device, taken as indicated at line 4—4 on Fig. 3, showing the mechanism in an operated position, with the current supply connections shown in section.

Fig. 5 is a face view of one of the current con-

ductor plugs, taken as indicated at line 5—5 on Fig. 4.

Figs. 6, 7 and 8 are transverse sections through the control mechanism, taken as indicated at lines 6—6, 7—7, and 8—8 respectively, on Fig. 3, with housing removed.

Fig. 9 is a fragmentary sectional view of the ratchet drive, taken at line 9—9 on Fig. 7.

For purposes of illustration, I have herein shown a support and control device constructed particularly for a sadiron, but it will be apparent that the device may be constructed for use with various other appliances. In Fig. 1 of the drawings I have shown an ironing board A provided with a laterally extending bracket B, which may project either from an end or side of the board. Removably mounted on the bracket is the supporting and control device constituting the present invention, and designated generally at C on which is supported a sadiron indicated at D, the device C being shown in an initial position of supporting adjustment for the iron. The iron D is provided with the usual electric cord E and a plug F connected in one of a pair of sockets on the device C, which are connected in series with a control switch, hereinafter described. Connected to the other socket is a plug G having a cord H with a plug J on its other end for connection to a conventional plug or socket of an electrical energy circuit.

The supporting and control device C includes a base 10, herein shown as of rectangular form, having downturned marginal flanges 11 at opposite sides. Mounted on said base, and connected thereto by bolts 12 is a housing 13 having its lower marginal edge offset, as may be seen in the drawings, to seat on and surround said base. The side walls and front wall of the housing are cut away as seen in Fig. 3 to provide for a limited range of vertical movement of a platform 14 which is hingedly connected at 15 to the rear upper end of said housing, the forward end being yieldingly supported in raised position by spring means hereinafter described. The platform 14 is limited in its downward movement by the under side thereof engaging the upper edges of said walls of the housing 13. Depending from the sides and front of the platform are skirt portions 16 and 17 which serve to complement the housing 13 to form a complete closure for the control mechanism; said skirt portions being preferably dimensional to telescope over the side and end walls of the housing 13. The upper surface of the platform 14 is provided with a frame-like member 18 having upstanding marginal

30

35

40

45

50

55

flanges 20 to confine the sadiron D thereon, and mounted within said frame 19 is a pad of suitable heat-resistant material 21 on which the iron is adapted to rest.

5   Mounted within the housing 13 on said base 10 is suitable mechanism having elements associated with the movable platform 14 and responsive to the movement thereof for interrupting the supply of electrical current to the appliance, after 10 the lapse of a predetermined interval of time. Said means comprises a frame structure 25 pivotally mounted on one end on a horizontally disposed shaft 26 mounted in brackets 27 secured to said base, while the other end of said frame is 15 yieldingly urged in an upwardly direction, as seen in Fig. 3, for returning and maintaining said platform 14 in a normal-inoperative position. The frame includes a pair of side members 29 and 30 the outer ends of which are connected together 20 by a shaft 31 on which is journaled a pair of transversely spaced-apart rollers 32, which, by movement of said frame 25 are at all times in yielding contact with the under side of the platform 14. Said frame 25 is urged in an upward 25 direction by a beam 34 one end of which is pivotally mounted on a pin 35, which, in turn, is supported in a pair of spaced-apart arms 36 of a bracket 37 connected to said base 10. Connected to the pivoted end of the beam 34 and extending 30 downwardly at substantially right angles thereto, is an arm 39 to the lower end of which is pivotally connected a clevis block 40, and connected to said block is a pair of springs 42 the opposite ends of which are connected to a fitting 43 mounted on 35 a screw 44 extending through a bracket 45 carried on said base 10. Mounted on the screw 44 are adjusting nuts 46 and 47 by virtue of which the block 43 may be moved in or out for varying the tension on the springs 42. The springs 42 acting on the lever arm 39 cause the free end of the beam 34 to yieldingly engage the under side of the shaft 31, which, through the medium of the rollers 32 tends to return and maintain the platform 14 in the position seen in Fig. 3.

45   Carried on the shaft 26 within the bifurcated end of the frame member 29 is a ratchet wheel 50 which is keyed to a hub 51 of a gear 52 which is journaled on said shaft. Said ratchet wheel 50 is actuated to rotate the gear 52 in response 50 to the downward movement of the platform 14 by the weight of an appliance upon said platform. The means for imparting motion from the platform to the ratchet wheel includes a connecting rod 54 connected at its upper end to the shaft 31 55 carried by said frame members 29 and 30 while its lower end is pivotally connected to an arm 55 of a bell crank 56 pivoted on a pin 57 journaled in the upstanding arms of a bracket 58 secured to said base 10. The other arm 59 of said bell 60 crank extends in an upward and rearward direction, and has a lever 60 pivotally connected thereto at its outer end; the opposite end of said lever 60 is pivotally connected between a pair of radius arms 61 which arms are journaled on the shaft 26 on opposite sides of the ratchet wheel 50; and pivotally connected to said radius arms 61 is a ratchet pawl 63 positioned for one-way actuation, to wit, by the downward movement of the frame 65 in response to depression or downward movement of the platform 14. It will be observed that the location and form of the ratchet and the driving connections therefor is such that the ratchet normally, by the influence of gravity, causes its hooked end to engage the teeth of the ratchet 70 wheel 50 in counter-clockwise movement, while 75

in the opposite direction of movement said pawl will be caused to cam over the teeth of the ratchet wheel.

80   Mounted on said shaft 26 inwardly of gear 52 is a gear 65 having a hub 66 on which is fixedly mounted a pinion 67. Disposed rearwardly of the shaft 26 is a frame 68 connected to said base 10 and providing journal support for a shaft 69 on which is rigidly mounted a pinion 70 meshing with the gear 52; and rigidly attached to said 85 shaft 69 is a gear 71 meshing with the pinion 67 which, with the gear 65, is loosely journaled on the shaft 26. Journaled in said frame 68 in substantially axial alignment with shaft 69 is a shaft 72 on which is rigidly mounted a pinion 73 meshing with gear 65. Securely attached to the outer end of said shaft 72 is a gear 74, which, in turn, meshes with a pinion 75 formed as part of the hub 90 of a brake wheel 77 which is journaled on a stub shaft 76, and supported in said frame 68. The 95 brake wheel is slightly eccentric, the purpose of which is to cause said wheel to serve somewhat in the nature of a fly-wheel for obtaining a more or less uniform speed of movement of the gear train.

100   It will now be apparent that when the frame 25 is depressed by the downward movement of the platform 14 the ratchet wheel 50 drives gear 52 and, in turn, pinion 70. Due to fixed mounting of pinion 70 and gear 71 of shaft 69 gear 71 drives 105 pinion 67 and gear 65 drives pinion 73 and gear 74 drives pinion 75 thus causing rotation of the brake wheel 77 and providing a gear train which, in effect, is a motion-reducing mechanism which, in the present case, serves as a timing mechanism.

110   Associated with the brake wheel 77 is a brake block 78 carried by a flexible band 79 hingedly mounted at 80, and at its lower end to the base portion of the frame 68, as may be seen in Fig. 3. 40 The upper end of said band 79 is rigidly secured to a control block 81 pivotally mounted at 82 in upstanding arms 83 on the top of the frame 68. Rigidly connected to said block 81 is a depending lever arm 82 the lower end of which is pivotally connected at 83 to a rod 84 the outer end of which is threaded in a block 85, pivotally connected to the lower end of a substantially vertically disposed lever 86. Said lever 86 is pivotally connected at 87 at its upper end to a bracket 88, 50 which, in turn, is rigidly attached to the base 10. Rigidly associated with the lever 86 is a cam 89 which is adapted to be engaged by a pin 90 projecting inwardly from the frame member 30.

115   It will be obvious that, as the platform 14 is moved downwardly under the weight of the appliance, it normally has a tendency to accelerate or increase its speed as it moves toward its lower limit. In order to insure a somewhat uniform rate of speed, the brake wheel 77 with the brake 60 block 78 is applied with a force somewhat proportional to what would be the normal speed of acceleration of the platform 14. Thus, as the platform moves downwardly, the stud 90 engages the cam 89 and through the lever 86 and rod 84 causes movement of the lever 82 to swing the pivot block 81 for moving the upper end of the band slightly upwardly, tending to straighten said band, and thereby apply slightly increased pressure of the shoe 18 against the brake wheel 70 77 and thus retard the speed of the gear train which is actuated by the downward movement of the platform, as above described.

120   As will be presently described, the platform 14 as it approaches its lower limit of movement, 75

opens a control switch for interrupting the current supply circuit for the appliance. To vary the period of time required for actuating the control switch, the cam member 89 may be adjusted with respect to stud 90 by adjustment of the rod 84 in the block 85; or, if desired, the cam 89 may be movably mounted on the lever 86 for accomplishing the same purpose, namely, variation of the time element required for causing 10 operation of the control switch after initiating downward movement of the platform 14.

The lever 86 and the linkage connected thereto to the brake band 79 is returned to normal inoperative position by a coil spring 81 connected 15 to said lever 86 and to a bracket 92 which is rigidly attached to a switch block 93 which is composed of insulating material, and secured on such base 10.

Mounted in the face of the switch block 93 is 20 a pair of spaced-apart electrical contacts 94 and 95 which normally are bridged by an electrical contact 96 carried on the end of a block insulating material 97 which, in turn, is rigidly mounted on a rock shaft 98 which is journaled in the 25 switch block 93 and in a support 99 rigidly attached to the base 10. Rigidly connected to the outer end of said shaft 98 is an upwardly extending arm 100 the upper end of which is curved, and extends between a pair of spaced-apart studs 30 102 and 103 on the beam 34. Surrounding the shaft 98 and reacting between the bracket 99 and the insulating block 97 is a compression spring 104 which tends to yieldingly maintain the contact 96 in a fixed position of adjustment.

35 It will now be apparent that, as the platform 14 moves downwardly the rollers 32 will be caused to ride on the under surface of said platform, thereby depressing the frame 25 and the beam 34 against the reaction of springs 42 and as said 40 platform approaches its lower limit of movement, the stud 102 engages the switch arm 100 cam-wise, swinging the contact block 97 in clockwise direction, and moving contact 96 out of engagement with contact 95 and thereby opening the 45 electrical current supply circuit to the appliance; and when the sadiron, D, or other appliance, is removed from the platform, said platform is returned to normal position by the force of springs 42 acting on the beam 34 and thence through frame 25 as above described. Such upward movement of the beam 34 causes the stud 103 to engage cam-wise with the under side of the lever arm 100 thereby swinging the contact block 97 to the 50 position seen in Fig. 3, at which the contact 96 again bridges contacts 94 and 95 for re-establishing the current supply circuit to the appliance.

The platform is arrested or stopped at its upper or normal supporting position due to the arrangement of rod 54, bell crank 56, lever 60, and 55 radius arms 61, which become blocked by lever 60 tending to push pivot of radius arms 60 in substantially horizontal rearward direction.

Associated with the contacts 94 and 95 are terminals 105 and 106, which, through conductor 60 wires 107, 108 are connected in series with the outlet sockets to which the plugs F and G are connected. Said outlet sockets include a block 65 109 of insulating material, mounted on said base 10, and one of said outlet sockets includes a pair 70 of spring contact members 110, 111 the latter being connected to the conductor wire 107, and the other socket includes a conventional pair of 75 spring contact fingers 112 and 113, the former being connected to the end of conductor wire 108; the other contacts 110 and 113 of the respective

sockets being connected to a conductor, in the form of a plate 117, to complete the series circuit, including the switch contacts 94 and 95. As above mentioned, the socket, including the contacts 110, 111 is adapted to be engaged by co-operating terminals 114, 115 of the plug F to which terminals are connected conductor wires comprising the cord E, which, in turn, through the medium of a suitable socket, supplies current to the electrical appliance, or, as herein indicated, the sadiron D. The other outlet, including the contact fingers 112 and 113 is adapted to be engaged by the prongs carried by a conventional plug G, which, through conductor wires comprising the cord H and plug J is adapted to complete the circuit to a source of electrical energy.

It will now be apparent that the control switch actuated in response to movement of the platform 14 is connected in series with the two sockets comprising the pairs of electrical contacts 110, 111 and 112, 113 respectively. Therefore, when the control switch is opened by movement of the contact 96, out of engagement with contact 95, the current supply to the appliance or sadiron is interrupted.

I have herein disclosed a novel and practical construction by virtue of which the electric current supply to an electrical appliance may be positively interrupted after the appliance is permitted to remain upon the support or platform 14 for a predetermined period of time, and the electric current supply circuit is immediately re-established upon removal of the appliance from the platform.

Although I have herein shown and described one embodiment of my invention, manifestly it is capable of substantial modification and rearrangement and substitution of parts without departing from the spirit and scope thereof, I do not, therefore, wish to be understood as limiting this invention to the precise embodiment herein disclosed, except as it may be so limited in the appended claims.

I claim:

1. A control for an electrical circuit, comprising in combination, a base, a support movably mounted on said base and adapted to provide a support for and be actuated by the weight of a body, means for controlling the speed of movement of the support and body, means for varying the speed of movement of the support for a body of given weight, a switch mounted on the base and connected in series in the electrical circuit to be controlled, and means for actuating the switch after said support has moved a predetermined amount.

2. A control for an electrical circuit, comprising in combination, a base, a support movably mounted on said base and adapted to provide a support for and be actuated by the weight of a body, means for controlling the speed of movement of the support and body, means tending to maintain a uniform rate of speed of said support and body, a switch mounted on the base and connected in series in the electrical circuit to be controlled, and means for actuating the switch after said support has moved a predetermined amount.

3. A control for an electrical circuit, comprising in combination, a base, a support movably mounted on said base and adapted to provide a support for and be actuated by the weight of a body, means for controlling the speed of movement of the support and body, means for varying the speed of movement of the support for a body

of given weight, means tending to maintain a uniform rate of speed of said support and body, a switch mounted on the base and connected in series in the electrical circuit to be controlled, and means for actuating the switch after said support has moved a predetermined amount.

4. A control for an electrical circuit, comprising in combination, a base including an upstanding wall forming a box-like structure, a movable platform hingedly connected at one end to the upper portion of the wall of said base, said platform being provided at certain of its marginal edges with depending skirt portions adapted to be moved in telescopic relation to the wall of said base, means acting on the opposite end of the platform for yieldingly maintaining it in approximately horizontal position, said platform being adapted to provide support for and be depressed by the weight of a body, means for controlling the speed of depression of the platform, a switch mounted on the base and connected in series in the electrical circuit to be controlled, and means for actuating the switch for opening the electrical circuit after said platform has been depressed a predetermined amount.

5. A control for an electrical circuit, comprising in combination, a base, a movable platform hingedly connected at one end to said base, means acting on the opposite end of the platform for yieldingly maintaining it in approximately horizontal position, said platform being adapted to provide support for and be depressed by the weight of a body, said means including a frame pivoted at one end to said base, and the opposite end yieldingly engaging the free end of the platform for normally urging it in an upwardly direction, means for controlling the speed of depression of the platform, a switch mounted on the base and connected in series in the electrical circuit to be controlled, and means for actuating the switch for opening the electrical circuit after said platform has been depressed a predetermined amount.

6. A control for an electrical circuit, comprising in combination, a base, a movable platform hingedly connected at one end to said base, means acting on the opposite end of the platform for yieldingly maintaining it in approximately horizontal position, said platform being adapted to provide support for and be depressed by the weight of a body, said means including a frame pivoted at one end to said base, and the opposite end yieldingly engaging the free end of the platform for normally urging it in an upwardly direction, a pair of transversely spaced-apart rollers carried on the free end of the frame and engaging the undersurface of said platform, means for controlling the speed of depression of the platform, a switch mounted on the base and connected in series in the electrical circuit to be controlled, and means for actuating the switch for opening the electrical circuit after said platform has been depressed a predetermined amount.

7. A control for an electrical circuit, comprising in combination, a base, a movable platform hingedly connected at one end to said base, means acting on the opposite end of the platform for yieldingly maintaining it in approximately horizontal position, said platform being adapted to provide support for and be depressed by the weight of a body, said means including a frame pivoted at one end to said base and the opposite end yieldingly engaging the free end of the platform for normally urging it in an upwardly di-

rection, a roller carried on the free end of the frame and engaging the under side of the platform, means for controlling the speed of depression of the platform, a switch mounted on the base and connected in series in the circuit to be controlled, and means connected to the switch and actuated by the frame after it has moved downwardly a predetermined amount for opening said switch.

8. A control for an electrical circuit, comprising in combination, a base, a movable platform hingedly connected at one end to said base, means acting on the opposite end of the platform for yieldingly maintaining it in approximately horizontal position, said platform being adapted to provide support for and be depressed by the weight of a body, said means including a frame pivoted at one end to said base, and the opposite end yieldingly engaging the free end of the platform for normally urging it in an upwardly direction, means for controlling the speed of depression of the platform, said control means including a gear train and a ratchet driving connection thereto, operatively connected to said pivoted frame, a switch mounted on the base and connected in series in the electrical circuit to be controlled, and means for actuating the switch for opening the circuit after said platform has been depressed a predetermined amount.

9. A control for an electrical circuit, comprising in combination, a base, a movable platform hingedly connected at one end to said base, means acting on the opposite end of the platform for yieldingly maintaining it in approximately horizontal position, said platform being adapted to provide support for and be depressed by the weight of a body, said means including a frame pivoted at one end to said base, and the opposite end yieldingly engaging the free end of the platform for normally urging it in an upwardly direction, means for controlling the speed of depression of the platform, said control means including a gear train, a ratchet driving connection thereto, operatively connected to said pivoted frame, and a brake for said gear train actuated to an increased degree as the acceleration of the platform increases in its downward movement, a switch mounted on the base and connected in series in the electrical circuit to be controlled, and means for actuating the switch for opening the electrical circuit after said platform has been depressed a predetermined amount.

10. A control for an electrical circuit, comprising in combination, a base, a movable platform hingedly connected at one end to said base, means acting on the opposite end of the platform for yieldingly maintaining it in approximately horizontal position, said platform being adapted to provide support for and be depressed by the weight of a body, said means including a frame pivoted at one end to said base, and the opposite end yieldingly engaging the free end of the platform for normally urging it in an upwardly direction, means for controlling the speed of depression of the platform, said control means including a gear train, a ratchet driving connection thereto, operatively connected to said pivoted frame, and a brake for said gear train actuated to an increased degree as the acceleration of the platform increases in its downward movement, means for varying the speed of depression of the platform for a body of given weight, a switch mounted on the base and connected in series in the electrical circuit to be controlled, and means for actuating the switch for opening the

electrical circuit after said platform has been depressed a predetermined amount.

11. A control for an electrical circuit, comprising in combination, a base, a movable platform 5 hingedly connected at one end to said base, means acting on the opposite end of the platform for yieldingly maintaining it in approximately horizontal position, said platform being adapted to provide support for and be depressed by the weight of a body, said means including a frame pivoted at one end to said base, and the opposite end yieldingly engaging the free end of the platform for normally urging it in an upwardly direction, means for controlling the speed of de-

pression of the platform, said control means including a gear train, a ratchet driving connection thereto, operatively connected to said pivoted frame, a brake for said gear train, and means responsive to the downward movement of said frame for actuating the brake to an increased degree as the acceleration of the platform increases in its downward movement, a switch mounted on the base and connected in series in the electrical circuit to be controlled, and means 10 for actuating the switch for opening the electrical circuit after said platform has been depressed a predetermined amount.

EDWIN H. DREYER.
